(57) **CLAIM**

The ornamental design for a facepack for an irrigation control box, as shown and described.

DESCRIPTION

FIG. 1 is a front, right, top perspective view of the facepack embodying our new design;

FIG. 2 is a back, left, bottom perspective view thereof;

FIG. 3 is a front elevation view thereof;

FIG. 4 is a back elevation view thereof;

FIG. 5 is a left-side elevation view thereof;

FIG. 6 is a right-side elevation view thereof;

FIG. 7 is a top plan view thereof; and,

FIG. 8 is a bottom plan view thereof.

All features illustrated in broken lines form no part of the claimed design.

1 Claim, 6 Drawing Sheets
